Primary Examiner — Karen S Acker*(74) Attorney, Agent, or Firm* — The Nath Law Group; Joshua B. Goldberg(57) **CLAIM**

The ornamental design for a synthetic resin paper, as shown and described.

DESCRIPTION

FIG. 1 is a front view of a synthetic resin paper.

FIG. 2 is a duplicate view of FIG. 1 showing where the details are taken.

FIG. 3 is a partially enlarged front view of the synthetic resin paper of FIG. 1; and,

FIG. 4 is another partially enlarged front view of the synthetic resin paper of FIG. 1.

The ornamental design for the synthetic resin paper has no substantial thickness. A bottom view is omitted since the bottom is flat and devoid of surface ornamentation. The broken lines represent boundaries and form no part of the claimed design.
